UNITED STATES PATENT OFFICE

JAMES MICHAL, OF CHICAGO, ILLINOIS, ASSIGNOR TO STORKLINE FURNITURE CORPORATION, OF CHICAGO, ILLINOIS

DROP-SIDE MECHANISM FOR CRIBS

Application filed December 30, 1927. Serial No. 243,669.

My invention relates to cribs of the drop-side type, and more particularly to the medium for operating the drop-side, it being my main object to provide a mechanism for this purpose which is of high efficiency.

A further object of my invention is to embody an action for the operation of the drop-side which is of an extremely simple character.

Another object of my invention is to design the novel mechanism for simple and easy operation.

A final, but nevertheless important object of my invention is to reduce the mechanism to extremely few parts, in order that the same may involve a small amount of labor and a minimum cost of materials.

With the above objects in view and any others that may suggest themselves from the specification and claims to follow, a better understanding of the invention may be gained by reference to the accompanying drawing, in which—

Figure 1 is a side elevation of a typical crib, illustrating my improvement;

Fig. 2 is an enlarged elevation of the parts immediately involved in the drop-side mechanism; and

Fig. 3 is a section on the line 3—3 of Figure 2.

It is a familiar fact that on cribs of the drop-side type, operating mechanisms of a more or less involved nature have been employed, these mechanisms often comprehending delicate parts which get out of order in a short time. Also, the costs of producing the structures have been high, and the medium of operations has in many cases required undue attention or effort. In cases of this nature, the mechanism is more of an impediment than a benefit, especially when it is considered that the crib is an article of light furniture and the operator is usually a person without mechanical skill. It has therefore been my intention to eliminate the above deficiencies, and many others that may be mentioned, and provide in my improvement a structure which accomplishes the objects contemplated above as fully as may be expected.

By specific reference to the drawing, 5 denotes the end posts, and 6 the angle-iron bed frame of a typical child's crib. The end posts are fitted with vertical guide rods 7 along which operates the drop-side 8, the latter actually consisting of the upper and lower rails 8 and intermediate rods or other spacing material 9. Full lines show the normal position of the drop-side, and finely dotted lines in Figure 1 denote the lowered position thereof.

In order that the drop-side may be suitably supported, I first attach by rivets 10 or other suitable means, the bases 11 of a pair of angle brackets 11a upon the frontal section of the frame bar 6. Between the brackets 11a I place a long bar 12, which has terminal reductions 12a which pass through slots 11b cut in the respective wings 11a. The reductions 12a are of arcuate cross section, and the slots 11b are of a similar curvature, as clearly shown in Figure 3, so that the bar 12 is capable of being rocked or rolled by reason of its curved bearing. In proximity to each bracket 11a, a plate 13 is welded or otherwise secured frontally upon the bar 12, this plate extending downwardly with a deflected portion 13a, whose direction is inwardly of the crib. The vertical portion of the plate 13 is cut with a vertically elongated slot 13b, in which rests a pin 14 projected inwardly of the crib from a hanger 15 whose base 15a is horizontal and adapted to be secured to the under side of the lower drop-side rail 8 by screws 16 or other means.

Since the drop-side is of a free nature, except for its guidance along the lateral rods 7, it will be clear that it rests in the proper normal position by the support of the pin 14 at the bottom of the slot 13b in the plate 13, which itself has support in the brackets 11a. However, if it is desired that the drop-side be lowered all that is necessary is that the deflected portion 13a of either plate 13 be given a light kick in a direction inward of the crib. This will cause the plate to swing in the direction of the arrow whereby to become disengaged from the pin 14, in which event the drop-side will lose its support and descend to lowered position, as indicated by the finely

dotted lines. The shock of this descent is usually cushioned by suitable buffers 17 at the lower ends of the guide rods 7.

It will be seen that the relation of the bar reductions 12a and slots 11b performs the function of a hinge for the plates 13, but does not entail the complications of the typical hinge. The peculiar construction I have devised enables the brackets 11a and the bar 12 to serve as supports and to embody between them a hinge relation without the aid of a single extra part, so that a simple and economical structure is the result. It is also significant that the slots 11b may be fashioned in a manner to perfectly control the strokes of the plates 13, so that these may operate at their best. The spacing of the operating units is such as to locate each of them near one end of the crib, so that the attendant may find it just as handy to operate the drop-side mechanism near one end of the crib as near the other. Naturally, it may be said that a single unit could suffice, since both units are identical; however, where a crib is of considerable length, it is advisable that a control be had near each end.

It is noted that the extensions 13a of the plates 13 are enlarged, this being to provide sufficient surface for the application of the attendant's toe without paying particular attention at what point the toe is applied. The extensions are thus of ample width to enable the attendant to actuate the mechanism without especial attention. While the operation to lower the drop-side has been explained, it will be apparent that nothing further than the usual raising of the same by hand is required to restore it to normal position. Accordingly, when the upper rail 8 is lifted, the pins 14 of the hangers 15 crowd the portions 13a of the plates 13 inwardly of the crib, so as to operate the plates as latches and locate them in a position to again receive the pins 14, at which time the plates 13 swing back to normal position shown to again support the drop-side as described.

While I have described and illustrated my invention in the preferred form, it will be seen that the same is capable of many minor changes and refinements, and I desire to claim such changes and refinements as coming within the spirit and scope of my invention.

I claim:—

1. A securing and releasing mechanism for the drop side of a crib comprising a hanger carried by the drop side, a pin extending laterally from the hanger, brackets mounted on the crib and formed with arcuate slots, a bar between the brackets on the crib having its extremities curved to seat in said slots and pivotally support said bar and a latch plate depending from said bar and slotted to receive said pin and furnish a support for the drop side.
2. A securing and releasing mechanism for the drop side of a crib comprising a hanger carried by the drop side, a pin extending laterally from the hanger, a pair of spaced brackets mounted on the crib and provided with curved bearing-forming slots, a bar between the spaced brackets on the crib having its extremities formed to seat in said curved slots and pivotally support said bar, and a latch plate on said bar and slotted to receive said pin and furnish a support for the drop side, said plate having a portion bent inwardly of the crib providing an inclined cam surface over which said pin is adapted to ride prior to said pin entering the slot in the latch plate.

In testimony whereof I affix my signature.

JAMES MICHAL.
